UNITED STATES PATENT OFFICE

162,785

NARROW ELASTIC FABRIC

Conrad J. Busch, Wyomissing, Pa., assignor to
Narrow Fabric Company, West Reading, Pa.,
a corporation of Pennsylvania

Application May 24, 1950, Serial No. 10,137

Term of patent 14 years

(Cl. D3—32)

To all whom it may concern:

Be it known that I, Conrad J. Busch, a citizen of the United States of America, residing at Wyomissing, county of Berks, State of Pennsylvania, have invented a new, original, and ornamental Design for Narrow Elastic Fabric, of which the following is a specification, reference being had to the accompanying drawing, forming a part thereof.

Figure 1 is an edge view of a portion of narrow elastic fabric embodying my new design, to which no tension is applied;

Fig. 2 is a front view of the narrow elastic fabric shown in Fig. 1;

Fig. 3 is an edge view, similar to Fig. 1, of the narrow elastic fabric as it appears when subjected to substantially maximum stretch; and

Fig. 4 is a front view of the narrow elastic fabric shown stretched as in Fig. 3.

The essential features of my design reside in the portions shown in full lines.

I claim:

The ornamental design for a narrow elastic fabric, as shown and described.

CONRAD J. BUSCH.
